UNITED STATES PATENT OFFICE.

FRITZ ALDENDORFF, OF ANTWERP, BELGIUM, ASSIGNOR TO WESTERN ELECTRIC COMPANY, OF NEW YORK, N. Y., A CORPORATION OF ILLINOIS.

AUTOMATIC TELEPHONE-EXCHANGE SYSTEM FOR SUBSCRIBERS' LINES WITH EXTENSION SETS.

1,130,697.

Specification of Letters Patent.

Patented Mar. 9, 1915.

Application filed September 4, 1913. Serial No. 788,146.

To all whom it may concern:

Be it known that I, FRITZ ALDENDORFF, a subject of the King of Great Britain, residing at 59 Rue Wouw, Mortsel, Antwerp, Belgium, have invented an Automatic Telephone-Exchange System for Subscribers' Lines with Extension Sets, of which the following is a true, clear, concise, and exact description.

10 My invention relates to automatic telephone systems and has to do more particularly with such systems connected to private telephone installations having an attendant's station at which the connections with extension stations are established.

15 The object of the invention is to provide circuits for the final selectors and the private installation by means of which the attendant at the private installation can, after he has been called, inquire the wishes of the calling subscriber, and then extend the connection to the wanted extension and replace his receiver without causing the selectors at the exchange to be restored to their normal condition as would be the case with the circuits generally known at the present time.

20 The release of the selectors of an automatic exchange with common battery working is effected in the known systems by a relay at the exchange responding to the rupture of the microphonic transmitter supply current on the replacement of the receiver. In circuits of this kind the attendant's station in a private installation would, after 25 he has inquired the wishes of the caller and made the connection with the desired extension, cause the selectors at the exchange to be restored to their normal condition if he did not wait until the called extension had 30 responded to the call and thus closed the microphonic supply circuit. From this it appears that if stepping relays or special stepping switching devices are not to be used at the final selector, which would permit of 35 several openings and closings of the wanted line circuit before releasing, a release circuit must be provided which is quite independent of the microphonic supply circuit. According to the invention this object is attained 40 by providing release circuits at the final selector and at the private installation which only respond to a momentary earthing of one or the other or both of the line limbs. The momentary earthing of one or the other

45 or both of the line limbs is effected by the hook switch at the attendant's station on the replacement of the receiver. The device which is provided on the attendant's station for connecting the extension sets to the telephone line is so arranged that the earth connection of the hook switch, which is used in order to effect the release, is broken whenever the attendant makes a connection with an extension set. In an installation of this kind it may happen that the extension set 50 connected to by the attendant does not respond to the call, so that the selectors of the exchange would be permanently held in their operative position. In order to prevent this contingency arising, a timed contact device is provided which, after a certain time has elapsed, effects the momentary earthing of the telephone line that is used for releasing the selectors. This timed contact device is controlled by an electromagnet 55 which stops the action of the timed contact the moment the called extension set responds, so that after the response of the extension set the release of the selectors is controlled entirely by the extension station. 60 The said electromagnet is preferably arranged to actuate a signal which informs the attendant as to whether a conversation is being carried on with an extension set or not. The electromagnet can also be used for 65 releasing the connection between the extension set and the exchange line.

65 The invention is shown in the accompanying drawing.

70 Figure 1 shows the circuits of the special release relay R^1, R^1 . Fig. 2 shows another way of connecting this relay. Fig. 3 represents the mechanical arrangement of the parts at the private installations. The invention has only to do with the elements of 75 the final selector of the automatic exchange that are concerned in the release of the selector and with the devices of the private installation. For the sake of simplicity and clearness only these elements are shown.

75 In Fig. 1 w, w^1 , represent the movable talk-
ing contact arms, k, k^1 , the fixed bank contacts of the final selector. To each pair of the bank contacts of the selector, an exchange line, 1, 2, leading to the private installation 80 is connected. R_s represents a relay which after the final selector has established the connection with the exchange line receives

current at the moment the attendant at M responds to the call. The ringing current RM is connected in the well known manner by ringing relay RR to the called line. 5 When the attendant raises his receiver from the switch hook the ringing current and the ringing relay RR is cut off in the well known manner by the actuation of a relay Rs of the final selector. When the receiver of 10 the attendant's set M is off the hook current flows from the exchange battery B through the relay Rs, winding R¹, armature 4, contact arm w, line limb 1, hook switch h, contact 3, winding of the induction coil 6, micro- 15 phonic transmitter m, line limb 2, contact h¹, contact arm u¹, armature 5, relay winding R¹, retardation coil D, to the other pole of the battery B. The windings R¹, R¹ are both on the same relay and act differentially so 20 that the current above described that flows through the two line limbs in series does not affect the armature 8 of the differential relay, but when the receiver at the attendant's station is replaced on the switch hook h, the 25 one line limb 1 is momentarily connected by the hook switch contact 10 with the earthed contact 9 and the lower relay winding is short circuited so that the neutralizing effect of the lower coil is destroyed and the 30 upper coil causes the armature to be attracted so as to close the circuit of the release magnet RM¹. It is to be noted that the contact 9, 10, of the hook switch h is arranged in the well known manner so as 35 to close the contact 9, 10 only on the receiver being replaced on the hook but not when the switch hook rises on the receiver being taken off. If the attendant after he has responded to a call finds that a connection 40 with an extension, for instance E¹, is desired, he depresses a button B¹ and thereby closes the contacts 12, 14, and at the same time removes the earthed connection e from the contact 9 of the switch hook by opening the 45 contact 11. On the attendant now replacing his receiver, the momentary earthing of the subscriber's line does not take place and the selectors at the exchange are not released. The releasing of the selectors upon 50 the termination of conversation is then performed by the called extension. Upon returning the switch hook to normal, it momentarily engages a grounded contact which connects conductor 1 of the line to earth 55 in the same way as this is effected by the attendant's set on the receiver being replaced on the switch hook. Should the extension fail to respond a timed contact TC, the spring of which is tensioned on the but- 60 ton B¹ being depressed, will earth the one limb of the subscriber's line after a certain time has elapsed and thus cause the release relay R¹R¹, to energize and release the selectors. If the extension set responds be- 65 fore the timed contact has been moved suffi-

ciently to earth the line, the winding RT which is included in series with said set receives current and attracts the armature 15 which has the effect of arresting the escape- 70 ment d by a stop 16; so as to stop the motion of the time contact TC and to prevent this contact from earthing the line limb 1 and effecting the release. On the receiver being replaced by the extension set E¹ the momentary earthing of the subscriber's line 75 causes the release of the selectors at the exchange in the manner already described. In addition to this the interruption of the current through the winding Rt causes a signal to be displayed to the attendant sig- 80 nifying that the exchange line has become free, and the button B¹ is released and in addition the catch 16 goes back into its normal position.

In Fig. 2 the coils of the release relay 85 R¹R¹ are connected in bridge, instead of in series to the line limbs as shown in Fig. 1. The working of this circuit is substantially the same as that of Fig. 1.

Fig. 3 shows the mechanical arrangement 90 of the keys B¹, B², Fig. 1 the timed contact TC, the releasing mechanism of the keys B¹, B², the electromagnet Rt which actuates said releasing mechanism, and of the signal that intimates to the attendant at M whether the 95 exchange line is being used by an extension set. The keys B¹, B² each have a shaft 19, which is capable of sliding up and down in a hole in a plate 18. The keys are main- 100 tained in their raised positions by springs 20. At the end of each shaft there is a cone 21 which, on the particular key being de- 105 pressed operates the contacts 11, 12, 14, Fig. 1. Each shaft has also another cone 22, which engages with a locking plate 23. This 110 locking plate is kept pressed against the cones 22 by a spring 24 bearing against the projection 25, the locking plate being ar- 115 ranged to revolve about a shaft 26. On a key B¹, B², etc., being depressed, the locking 120 plate 23 is moved outwardly from the shaft 19 and presses against the bent end 27 of a lever 28, which moves about a pivot 29 and has a toothed sector 30 at its lower end. The depression of the button and the en- 125 suing outward movement of the locking plate 23 has the effect of moving the sector 30 inwardly so as to cause a wheel 31 to revolve upon a pivot 32 in the direction in- 130 dicated by an arrow. This movement of the sector 30 has the effect of tensioning a spring 44 and when the bent upper portion 33 of the locking plate slides over the upper end of the cone 22 of the depressed key the spring 44 will exert a pull upon the sector 135 30 and will turn the wheel 31 toward its normal position. Attached to the wheel 31 is the contact TC. The movable contact TC brushes past fixed contact 17. In moving away from its normal position, an insulated 140

surface 34 of the time contact TC will brush past the fixed contact 17, but when the wheel 31 is moved toward its normal position by the tension of the spring 44, the lower surface of the contact TC will brush past the fixed contact 17 and make contact just before the wheel 31 reaches its normal position. If the extension set corresponding to the depressed button—for instance B¹, responds to the call within a reasonable time, the energization of the magnet Rt will cause the attraction of the armature 15 and bring a catch 16 into the path of an extension 35 attached to an escapement d, which controls the movement of the wheel 31. Thus when the extension set responds to the call, the catch 16 will prevent the further movement of the wheel 31 into its normal position and will thereby prevent contact being made between TC and 17. During the attraction of the armature 15 a target 36 will become visible behind an opening 37 at the attendant's station M, and this will intimate to the attendant that the extension set has responded and is using the exchange line. When the armature 15 is attracted by the magnet Rt a pin 38 brushes past an extension 39 attached to a spring 40 and tends to push the locking plate 23 more firmly against the cone 22. The spring 39 gives way slightly to the pressure of the pin 38 when the armature 15 is pulled downward, but when the magnet Rt is deenergized and the armature 15 is pulled back into its normal position by a spring 41, the other side of the pin 38 brushes against the extension 39 and the lower end of the spring 40 now butts against an extension 42 attached to the plate 23, and does not give way to the pressure of the pin 38 but moves the locking plate 23 outwardly and releases the depressed key—for instance B¹, which is now pushed upward into its normal position by the spring 20. In case the extension set does not respond within a reasonable time after connection has been made by the attendant, the electromagnet Rt which is in series with the upper winding R¹ will be momentarily energized when the contact TC brushes against the fixed contact 17 on the return movement of the wheel 31. This momentary energization of the electromagnet Rt will cause the oscillation of the armature 15 and thus will cause the oblique plate 38 to move the locking plate 23 and release the depressed key, for instance B¹. In order to prevent the escapement d from being arrested by the catch 16 when contact is made between TC and 17, a suitable projection 43 is fixed to the wheel 31, which pushes the catch 16 out of the range of the extension 35 of the escapement d. Thus the catch 16 will only become effective if the contact TC has been moved beyond fixed contacts 17 by the depression of a key B¹, B², etc.

I claim:—

1. In a telephone exchange system in which connections are established by selector switches, telephone stations each comprising an attendant's station and an extension station, a special selector releasing circuit extending to each said attendant's station and controllable at this station, and means for transferring the control of the said special selector releasing circuit to the said extension station prior to the response of the subscriber at said station. 70

2. In a telephone exchange system in which the connections are established by selector switches, telephone stations each comprising an attendant's station and a plurality of extension stations, a special selector releasing circuit extending to each attendant's station and controllable at this station, and means for transferring the control 80 of the said special selector releasing circuit to any of the said plurality of extension stations prior to the response of the subscriber at said station. 85

3. In a telephone exchange system in which the connections are established by selector switches, telephone stations each comprising an attendant's station and an extension station, a microphonic battery supply circuit extending from the said exchange system to a said attendant's station, a special selector releasing circuit extending to each said attendant's station and controllable at this station, means for transferring the control of the special selector releasing circuit to a said extension station. 95

4. In a telephone exchange system in which the connections are established by selector switches, telephone stations each comprising an attendant's station and an extension station, a microphonic battery supply circuit extending from the said exchange system to a said attendant's station, a special selector releasing circuit formed of a part of the said microphonic battery supply circuit said special selector releasing circuit being controllable at a said attendant's station, means for transferring the control of the said special selector releasing circuit to a said extension station. 105 113

5. In a telephone exchange system in which the connections are established by selector switches, telephone stations each comprising an attendant's station and a plurality of extension stations, a two-position 120 switch at each said attendant's station, a conductor connected to each of the said two-position switches to a contact at a point between the two positions of the said two-position switch, a special selector releasing 125 circuit extending to each said attendant's station and including the said conductor which is connected to the said two-position switch, said special selector releasing circuit being controllable at the said attendant's 130

- station, means for opening the said conductor connected to the said two-position switch and for transferring the control of the said special selector releasing circuit to a said extension station.
6. In a telephone exchange system in which the connections are established by selector switches, telephone stations each comprising an attendant's station and an extension station, a microphonic battery supply circuit extending from the said exchange system to a said attendant's station, a line extending from the said attendant's station to its extension station, a two-position switch at the attendant's station which controls the said microphonic battery supply circuit, a switch for connecting the said microphonic battery supply circuit to the said extension line, a conductor connected to the said two-position switch and to the said extension switch, a special selector releasing circuit extending to each attendant's station and including the said conductor which is connected to the two-position switch and the extension switch, contacts on the said extension switch for connecting the said microphonic battery supply circuit to the said extension line and for opening the said special selector releasing circuit.
7. In a telephone exchange system in which the connections are established by selector switches, telephone stations each comprising an attendant's station and a plurality of extension stations, a special selector releasing circuit extending to each attendant's station and controllable at this station, means for transferring the control of the said special selector releasing circuit to any of the said plurality of extension stations, a timed contact, means for actuating the timed contact which causes it to close the special selector releasing circuit a certain time after the actuation of the means for transferring the control of the said special selector releasing circuit.
8. In a telephone exchange system in which the connections are established by selector switches, telephone stations each comprising an attendant's station and an extension station, a special selector releasing circuit extending to each attendant's station and controllable at this station, means for transferring the control of the said special selector releasing circuit to a said extension station, a timed contact, means for actuating the timed contact which causes it to close the said special selector releasing circuit a certain time after the actuation of the means for transferring the control of the said special selector releasing circuit.
9. In a telephone exchange system in which the connections are established by selector switches, telephone stations each comprising an attendant's station and an extension station, a special selector releasing circuit extending to each attendant's station and controllable at this station, means for transferring the control of the said special selector releasing circuit to a said extension station, a timed contact, means for actuating the timed contact that causes it to close the said special selector releasing circuit a certain time after the actuation of the means for transferring the control of the said special selector releasing circuit to a said extension station, a conductor connected to the said extension switch, an electromagnet for stopping the action of the said timed contact, said electromagnet being controlled by a said extension station.
10. In a telephone exchange system in which the connections are established by selector switches, means for restoring said switches, telephone stations each comprising an attendant's station and an extension station, a microphonic battery supply circuit leading from the said attendant's station to a said extension station, means for connecting the said microphonic battery supply circuit to the said extension line, a special releasing circuit leading to a said attendant's station and formed of a part of a said microphonic battery supply circuit the said special releasing circuit being extended to the said extension line by the said means for connecting the said microphonic battery supply circuit to the said extension line, said restoring means being actuated only upon the closure of the said releasing circuit.
11. In a telephone exchange system in which the connections are established by selector switches, telephone stations each comprising an attendant's station and a plurality of extension stations, a microphonic battery supply circuit leading from the said selector switches to a said attendant's station, a special selector releasing circuit formed of part of such microphonic battery supply circuit and including a two-position switch at the said attendant's station which is normally held in the one position, and a conductor connected to the said two-position switch, said special release circuit being capable of being closed when the said two-position switch is moved into the said one position, means for opening said conductor and for extending the special releasing circuit to any one of the said extension stations.
12. In a telephone exchange system in which the connections are established by selector switches, telephone stations each comprising an attendant's station and an extension station, a microphonic battery supply circuit leading from the said selector switches to a said attendant's station, a special releasing circuit for the said selector switches formed of a part of a said microphonic battery supply circuit, a switch at

the attendant's station for controlling the said release circuit, means for transferring the control of the said releasing circuit from the said switch to the said extension station, 5 and a timed contact for closing the said special releasing circuit.

13. In a telephone exchange system in which the connections are established by selector switches, telephone stations each comprising an attendant's station and an extension station, a main line leading from the said selector switches to a said attendant's station, an extension line leading from the attendant's station to the extension station, a lockable switch for connecting the main line to the extension line, a release circuit for the said selector switches, an electromagnet included in the said release circuit for unlocking the said lockable switch.
20. 14. In a telephone exchange system in which the connections are established by selector switches, telephone stations each comprising an attendant's station and an extension station, a main line leading from the said selector switches to a said attendant's station, an extension line leading from the said attendant's station to the extension station belonging thereto, an extension switch for connecting the said main line to the extension line, a locking device for locking the said extension switch, a releasing circuit for the said selector switches, a timed contact for closing the said releasing circuit, an electromagnet for unlocking the said extension switch and for arresting the action of the said timed contact.

15. In a telephone exchange system in which the connections are established by selector switches, telephone stations each comprising an attendant's station and an exten-

sion station, a main line leading from the said selector switches to the said attendant's station, an extension line leading from the attendant's station to the extension station, 45 an extension switch for connecting the said main line to the extension line, a locking device for locking the said extension switch, a releasing circuit for the said selector switches, a timed contact for closing the said 50 releasing circuit, a signal at the attendant's station, an electromagnet for unlocking the said extension switch for arresting the action of the said timed contact and for displaying the said signal.

16. In a telephone exchange system in which the connections are established by selector switches, telephone stations each comprising an attendant's station and an extension station, a main line leading from the 60 said selector switches to the said attendant's station, an extension line leading from the attendant's station to the extension station, an extension switch for connecting the said main line to the extension line, a locking device for locking the said extension switch, 65 a releasing circuit for the said selector switches, a timed contact for closing the said releasing circuit, a signal at the attendant's station, an electromagnet included in the 70 said releasing circuit said electromagnet operating to unlock the said extension switch to arrest the action of the said timed contact and to display the said signal.

In witness whereof, I hereunto subscribe 75 my name this 14th day of August, A. D. 1913.

FRITZ ALDENDORFF.
